DOOR SWITCH

David Conlan, New York, N. Y., assignor to Conlan Electric Corporation, Brooklyn, N. Y.

Application April 19, 1943, Serial No. 483,688

10 Claims. (Cl. 200—54)

The invention herein disclosed relates to switches, such as used aboard ships, to assure that all lights in a stateroom will go off when the door to such room is opened.

General objects of the invention are to provide a sturdy, reliable type of switch in a unitary form, which can be quickly and easily mounted in a door frame, in position to be controlled by the door and in which all parts will be enclosed and properly protected.

Special objects are to provide switch actuating mechanism of simple construction and few parts, easily assembled, requiring no supervision or attention and not likely to get out of order.

A further special object is to provide simple and practical means for enabling the switch to be locked in inoperative condition, so that it will not be controlled by the door, when such a situation becomes necessary or desirable.

Other objects and the novel features by which all purposes of the invention are attained will appear or are set forth in detail in the following specification.

The drawing accompanying and forming part of the specification illustrates one commercial embodiment of the invention, but it is to be understood that structure may be modified and changed as regards the present illustration, all within the true intent and scope of the invention as hereinafter defined and claimed.

Fig. 1 in the drawing is a front view of the switch unit as applied to a door casing, with the cover of the box structure removed and the parts in the open circuit condition.

Fig. 2 is a vertical sectional view of the complete unit as on substantially the plane of line 2—2 of Fig. 1.

Fig. 3 is a horizontal sectional view on substantially the plane of line 3—3 of Fig. 2, but showing the door actuated plunger locked in, with the switch in closed circuit condition.

Fig. 4 is a view similar to Fig. 1, illustrating the parts in the last described relation.

The protection of all the parts of the switch and the combination of the same in a single unitary structure are accomplished by mounting and enclosing all such parts within a box 5 and cover 6.

The switch mechanism is indicated at 7, as a toggle switch unit of a size fitting closely within the lower end of the box and confined in that position by overstanding lugs 8 and 9, projecting inwardly from the back wall of the box and from the cover over opposite edges of the insulating switch base 10. In this manner, the switch

is mounted and held in place in the box by the simple act of locating it in the lower end of the box beneath the back lug 8, for in this position, the cover lug 9, will engage over and hold the switch base when the cover is applied.

As indicated in Figs. 2 and 3, the cover lug 9, can slide over the top of the switch base when the cover moves inwardly under the pull of the securing screws 11, in compressing the sealing gasket 12, seated in the groove 13, in the cover, in engagement with the rim of the box.

The switch actuating mechanism is shown as comprising a door engageable plunger 14, sliding through a stuffing gland bearing 15, in one side of the box above the switch and engaging one end of a lever 16, pivoted on the back wall of the box and arranged to operate the toggle lever 17, of the switch.

Specifically, the plunger is shown as having a head 18, at its inner end to slidably engage the rounded or cam-shaped edge 19, of lever 16, and to act as a stop engageable with the inner end of the bearing 15, to limit the outward projection of the plunger.

The switch actuating lever is shown pivoted intermediate its ends on a screw stud 20, set in the end of a post 21, projecting from the back wall of the box.

The other end portion of lever 16, is shown as angled inwardly at 22, in spaced relation over the mounting post 21, and as having the inwardly offset extension 23, in line with the toggle lever 17.

The inset end portion of the actuating lever is indicated as longitudinally slotted at 24, to slidably receive the inner end of a screw pin 25, fixed to the end of toggle lever 17.

To provide a firm, secure mounting of the actuating pin 25, in the end of the toggle lever, said pin is shown in the form of a screw extending through a U-shaped bracket or clip 26, embracing the end portion of such lever and as having screw engagement at 27, in the inner arm of such bracket. By tightening such screw, the bracket will be clamped about the end portion of the toggle lever and the screw thus firmly anchored in place on the lever.

The switch is biased in the circuit opening direction by means of a coiled spring 28, loosely engaged about the post 21, in back of the forward, pivoted end portion of lever 16, said spring being anchored at its inner end to the back wall as by means of a screw 29, and having its outer end engaged over the edge of the inwardly angled and offset portions 22, 23, to rock the lever in a clock-

wise direction, Fig. 1, to both project the plunger and throw the switch to the off position.

In Figs. 1 and 4, the plane of the opposing face of the door is indicated at 30. From these views, it will be seen that a relatively slight closing or opening movement of the door, acting through plunger 14, on the short arm of the lever 16, will, through the long arm of the lever throw the switch fully from the off to the on position or vice versa. This makes it possible for the occupant of the room to have illumination immediately the door is fully closed and makes certain that the lights in the room will all be thrown off immediately the door starts to open, that is, to the appreciable extent where lights would be dangerous or objectionable.

The wiring connections are not shown, but it will be understood that the wiring brought in through the junction connection 31, to the terminals 32, on the switch, will be such as to control all lighting or other similar outlets in the room.

The box is shown as having an inwardly extending projection 33, on its upper wall forming a barrier to prevent any possibility of wires brought into the box interfering with operation of the switch throwing mechanism.

To provide for locking the switch in the circuit closed relation, so that it will not be affected by opening and closing movements of the door, a lock screw is indicated at 34, extending through a packing gland 35, in the cover, in position to pass behind the head 18, on the inner end of the plunger, thus to secure the plunger in its inner position and hold the lever 16, in the switch closed position.

The mechanism is easily assembled, it only being necessary to insert the plunger in its bearing, locate the spring over the post and then secure the lever in its pivoted position on the post. The switch can then be dropped in position in the lower end of the box, caught at the back beneath the holding lug 8 and with the pin 25, extending through the slot in the actuating lever. Then when the cover is put on, the switch will be finally secured in this position and the locking screw 34, located to cooperate with the head 18, of the plunger.

In this closed position of the box, all the parts are sealed in water and gas tight relation and protected from mechanical injury.

The switch box unit can be quickly and accurately mounted on the door jamb by simply placing it so that the plunger will be pushed all the way in when resting against the face of the closed door. The mounting lugs 36, provide means for securing the box in this relation and the cover screw lugs 37, projecting from the sides of the box provide means for limiting the extent of the inward push on the plunger by the face of the door (Fig. 4).

The switch is indicated as of the double pole, double break type, having four terminals 32, which can be connected in on a loop taken from the two supply wires entering a room. The ready removability of the switch from the box, when the cover is released, facilitates connection of the wires with these four terminals.

The U-shaped clip 26, which clamps about the end of the switch lever, reinforces that lever, a particularly desirable feature in those switches having toggles of more or less frangible insulating material. This mounting also prevents any twisting of the screw pin and provides a metal-to-metal engagement between the toggle lever and the swinging lever which actuates it.

If desired, a bowed spring or compressible material 40, may be secured to the inside of the cover in the space between the front of the switch base and the cover, Fig. 2, allowing for compression of the packing 12, to avoid any looseness of the switch in the box.

The abutment 33, Figs. 1 and 4, may be disposed so as to serve as a stop engageable by the head 18, to prevent the plunger being thrust in 10 too far, thus protecting the switch against injury from such a cause.

As particularly shown in Figs. 2 and 3, the forwardly and rearwardly offset end portions of lever 16, provide a compact and desirable arrangement of parts, this allowing for a long and powerful coiled spring and the placing of the actuating plunger at the front of the box and the connection with the switch toward the back of the box, and this enabling an enclosure of relatively small size.

What is claimed is:

1. A switch of the character disclosed, comprising a watertight and gas tight enclosure, a door operable plunger projecting from said enclosure, 25 a switch removably positioned in said enclosure, a lever pivoted intermediate its ends within said enclosure and engageable at one end by the inner end of said plunger and connected at its opposite end to operate said switch, a spring tensioned to 30 swing said lever in the direction to project said plunger and shift the switch to open circuit relation, said enclosure comprising a box having a removable cover and means on said cover for engaging, positioning and removably holding the 35 switch within the box, said switch and lever having a detachable connection separable to permit free removal of the switch from the box and from said lever when the cover is removed.

2. A switch of the character disclosed, comprising 40 a watertight and gas tight enclosure, a door operable plunger projecting from said enclosure, a switch positioned in said enclosure, a lever pivoted intermediate its ends within said enclosure and engageable at one end by the inner end of 45 said plunger and connected at its opposite end to operate said switch, a spring tensioned to swing said lever in the direction to project said plunger and shift the switch to open circuit relation, said switch having a toggle lever actuated by said 50 pivoted lever, a U-shaped clip embracing said toggle lever, a screw passing through said toggle lever and clamping the arms of said U-shaped clip against said toggle lever, the end of said screw projecting from said clip and the swinging 55 lever having a slot engageable by the projecting end of said screw.

3. A stateroom door switch, comprising a box 60 having a removable cover, a switch seated in the lower portion of said box, said switch being shaped to fit closely in said lower portion of the box and removably positioned and held in such position by said removable cover, a post projecting from the back wall of the box above said switch, a coiled spring supported on said post, a lever pivoted on said post having a dependent 65 arm operably connected with said switch and an upwardly projecting arm, said lever being engaged by said spring and a plunger projecting through the side of the box into position to engage and operate the upwardly projecting arm of said lever.

4. A stateroom door switch, comprising a box 70 having a removable cover, a switch seated in the lower portion of said box and removably positioned and held in such position by said remov-

able cover, a post projecting from the back wall of the box above said switch, a coiled spring supported on said post, a lever pivoted on said post having a dependent arm operably connected with said switch and an upwardly projecting arm, said lever being engaged by said spring, a plunger projecting through the side of the box into position to engage and operate the upwardly projecting arm of said lever and a lock screw mounted on the cover in position to be projected inwardly into holding engagement with the inner end of said plunger.

5. A switch of the character disclosed, comprising a box, a post projecting forwardly from the rearward wall of said box, a lever pivoted intermediate its length on said post and having forwardly and rearwardly offset ends, the rearwardly offset end of said lever being longitudinally slotted, an operating plunger engageable with the forwardly offset end of said lever, a switch removably engaged in the bottom of said box and having an upwardly projecting actuating lever provided with a rearwardly projecting pin operably engaged in the slot in the rearwardly offset end of said lever and a coiled spring on said post acting on said lever.

6. A switch of the character disclosed, comprising a box and cover and a compressible sealing gasket between said box and cover, means securing said cover and adjustable to compress said sealing gasket to a desirable extent, a switch located in and bodily removable as a unit from within said box, positioning lugs on said box and on the inside of said cover engageable with said switch, compressible holding means on the inside of said cover and engageable with said switch and means for actuating said switch including a projecting actuating extension.

7. A switch of the character disclosed, comprising a box having a removable cover, a forwardly projecting lug on the back of the box and a rearwardly projecting lug on the inside of the cover, both located a distance above the bottom of the box, a switch having a base removably fitting in the bottom portion of the box beneath said lugs and thereby confined in definite position when said cover is on the box, said switch having an upwardly projecting lever for actuating the same, a lever pivotally mounted in the box above said switch and having an upwardly projecting arm and a downwardly projecting arm, said downwardly projecting arm having a detachable operating connection with said switch lever, a plunger operating through the side of the box and having operative engagement with said upwardly

50 projecting arm of the lever and spring means for effecting yielding projecting movement of said plunger.

8. A switch of the character disclosed, comprising a box having a cover, a switch having a base fitting the bottom portion of said box and thereby located in definite position in the bottom of the box, means on the cover engaging said switch base to removably hold the switch thus definitely positioned in the bottom of the box, said switch having an upwardly projecting switch actuating lever, an operating lever pivotally mounted in the box above said switch lever, a detachable operating connection between the lower end of said operating lever and said switch lever, permitting free removal of the switch from the box when the cover is separated from the box, a plunger operating through the side of the box and having operative engagement with said operating lever and spring means for effecting yielding projection of said plunger.

9. A switch of the character disclosed, comprising a box having a removable cover, a switch having a base fitting in the bottom portion of said box and thereby removably positioned in a definite location, said cover having means engaging said switch base to retain the same so located, said switch having an upwardly projecting lever for actuating the same, a clip embracing said switch actuating lever, a screw passing through said clip and clamping the same in position on said lever, said screw projecting beyond said clip, an operating lever pivoted in the box above said switch and slotted to loosely receive the projecting portion of said screw and whereby said operating lever and switch lever may be detachably connected by the mounting of said switch in said box, a plunger projecting from the box and in operative engagement with said operating lever and spring means for effecting the yielding projection of said plunger from the box.

40 10. A switch of the character disclosed, comprising an enclosure, a switch mounted in said enclosure and bodily removable therefrom as a complete unit, said switch having a projecting lever for actuating the same, an operating lever pivotally mounted in the enclosure and detachably connected with said switch lever, a plunger operating through the wall of the enclosure and having operative engagement with said operating lever, spring means for effecting projection of the plunger and means engageable with said plunger for locking the same in retracted position within the box.

55 DAVID CONLAN.
